UNITED STATES PATENT OFFICE.

ARTHUR M. DENNING, OF CRETE, NEBRASKA.

DEVICE FOR REBABBITTING CONNECTING-RODS.

1,264,618.

Specification of Letters Patent. Patented Apr. 30, 1918.

Application filed April 6, 1916. Serial No. 89,378.

To all whom it may concern:

Be it known that I, ARTHUR M. DENNING, a citizen of the United States, residing at Crete, in the county of Saline and State of 5 Nebraska, have invented certain new and useful Improvements in Devices for Rebabbitting Connecting-Rods, of which the following is a specification.

This invention relates to a device for rebabbitting connecting rods, and especially 10 that type of rod used by a certain make of automobile.

The invention consists of a combined support, mold and core, and of certain specific 15 features of construction hereinafter described, pointed out in the claims and shown in the accompanying drawings in which:—

Figure 1 is a side elevation showing the complete device in use.

20 Fig. 2 is a face view, one section of the mold and core being removed.

Fig. 3 is a longitudinal section, a connecting rod being also shown in position and rebabbitted.

25 Fig. 4 is a face view of the removable portion of the mold and core.

In the drawings 1 designates a standard which may be supported in an upright position by any suitable means.

30 The upper portion of the standard is angled and offset as at 2 and the lower portion carries a wrist pin 3. Adjacent the pin 3 is a threaded opening 4. Midway the ends the standard has lateral extensions 5 which are provided with lugs 6 at right angles to the face of the standard, and through 35 said lugs work cooperating thumb screws 7.

A thumb screw 8 also works through the opening 4.

40 A cylindrical block 9 is secured to the inner face of the offset portion 2 by means of a screw 10, but for purposes of description may be considered as the fixed member of the mold.

45 This block carries a core 11 and is provided with an annular groove 11^a encircling the base of the core and adapted to receive a flange of a connecting rod 19.

A similar coöperating block 12 is provided 50 with a core portion 13 and grooves 14 and with a central opening 15 adapted to fit over a pin 16 projecting centrally from the core 11, the outer end portion of the pin being threaded and the core 12 being locked 55 thereon by a nut 16^a.

The core 13 has a recess 17 and the core 11 a pin 18 which engages said recess, so that there is no relative movement between the two core portions when secured in place.

In use the connecting rod 19 has the end 60 to be rebabbitted fitted over the core 11 and the core portion 13 is then placed in position, the two core sections engaging, and the flanges of the rod overlapping the grooves 11^a and 14, respectively, and the 65 other end of the rod is slipped over the wrist pin 3. It is locked and centered in position by the thumb screws 7.

These connecting rods as at present made are provided with an opening 20 and through 70 this is poured the Babbitt metal 21. Any joints in the mold may be wrapped or packed with thread or asbestos, and in practice I find that a light strand of asbestos or cotton wick packing at the joints *a* is all 75 that is required to prevent escape of the metal.

When the work has been completed the screw 8 will serve to force the rod off the wrist pin 3.

The simplicity and advantages of the device will be obvious to those using devices of this general character.

What I claim is:

1. In a device of the kind described, a 85 connecting rod support comprising a standard having a pin adjacent one end and offset at the other end, a core block section carried by the offset portion of the standard, and a coöperating core block section 90 adapted to be supported from the first section and detachable therefrom.

2. In a device of the kind described, a standard, the upper end of the standard being offset, a block carried by and within the offset, 95 a core integral with the block and having an annular groove at its base and a centrally projecting pin, a second block having a core portion adapted to fit over said pin and engage the core of the first mentioned block, 100 and having also an annular groove, and means for locking the core sections together.

3. In a device of the kind described, a standard having a pin adapted to engage the 105 wrist-pin opening of a connecting rod, said standard being offset, a combined mold and core section carried by the offset portion and adapted to engage the head of the connecting rod, and a similar, coöperating mold 110

and core section adapted to engage said head and to be locked to the first mentioned mold and core section.

4. In a device of the kind described, a standard, a pin carried by the standard adjacent one end, said standard having a threaded opening adjacent said pin, a thumb screw working through said opening from the side opposite the pin, lateral extensions formed on the standard, lugs carried by said extensions at right angles to the standard, adjusting screws working through said lugs, and mold and core sections supported from the standard at the end opposite said pin.

5. In a device of the kind described, two 15 detachable mold and core sections, each section comprising a block, and a core, the blocks being grooved at the base of the cores, one of said blocks and cores having a central opening, a pin carried by the core 20 of the other block adapted to fit said opening, and means for supporting the block the core of which carries said pin, said means also supporting a connecting rod during process of rebabbingting.

25
In testimony whereof I affix my signature.

ARTHUR M. DENNING.
